UNITED STATES PATENT OFFICE.

JOSEPH WESOLIK, OF BELLEVILLE, ILLINOIS, ASSIGNOR OF ONE-FOURTH TO EWALL LUETSCHER, OF BELLEVILLE, ILLINOIS, AND ONE-FOURTH TO LUDWIG KRIBBEN, OF CLINTON, MASSACHUSETTS.

COUPLER.

Application filed August 27, 1923. Serial No. 659,471.

To all whom it may concern:

Be it known that I, JOSEPH WESOLIK, a citizen of the United States, residing at Belleville, in the county of St. Clair and State of Illinois, have invented a certain new and useful Coupler, of which the following is a specification.

This invention relates to couplers and more particularly to a coupler for coal mine cars, and, has for its object to provide a coupler which is a distinct and practical improvement to overcome certain practical objections to, and defects in, mine car couplers of the standard type.

15 A further object of the invention is the provision of a coupler which will be simple in construction, strong, durable and easily and quickly manipulated when uncoupling cars and which will be automatic and highly efficient in its coupling operation.

With the above and other objects in view, the invention consists in the novel features of construction, arrangement and combination of parts and their equivalents herein-after more fully described and finally pointed out in the claims hereto appended.

Referring to the accompanying drawings forming a part of this specification, wherein like characters of reference denote similar parts throughout the several views:

Fig. 1, is a plan view of a coupler embodying the features of my present invention.

Fig. 2, is a side elevation thereof.

Fig. 3, is a horizontal sectional view of the coupler.

Fig. 4, is a view of the coupler, partly in side elevation and partly in vertical sectional elevation with the locking mechanism shown as raised or unlocked to permit of the two coupling heads being disconnected.

Fig. 5, is a sectional view similar to Fig. 3, but showing the coupler heads in their engaged position which position they assume when two cars are bumped together.

Fig. 6, is a view partly in front elevation and partly in sectional elevation of one of the coupler heads of the coupler.

Fig. 7, is a detail in side elevation of one of the coupler heads showing the connecting bar thereof in full lines in one position and in dotted lines in another position.

It will be here observed that the type of coupler I have herein illustrated and de-

scribed consists of two coupler heads, each of 65 different construction, one head of which is applied to one end of a car body and the other head to the opposite end of the car body, which permits the cars to be automatically coupled, but manually uncoupled. 60

One of the coupling members of the coupler, which may for convenience be called a female coupling head and comprises a hollow head designated 1 having the bottom wall 2, the side walls 3, the end wall 4 and the top wall 5. The front end of the coupler head 1 is open, as at 6, and the sides thereof are bounded by the two opposed vertically disposed stop flanges 7 which are directed toward each other, as clearly shown in Figs. 70 3, 5 and 6. The side walls 3 are each provided with the bumping flange 8 which is directed outwardly from each side wall 3 a suitable distance to strengthen the head, as clearly shown in Figs. 1, 2 and 6. The front 75 outer corners of each bumping flange 8 is rounded, as at 9. The forward end of the bottom wall 2 of the coupler head 1 is beveled, as at 10, as clearly shown in Fig. 4.

A suitable lock plate 11 is positioned to the rear of the front opening 6 of the coupler head 1. The lock plate 11 is hingedly supported by means of a suitable pin 12, the ends of which pin extend into opposed vertically disposed slotted openings 13 in the side walls 3 of the coupler head 1 to permit rearward arcuate movement of the lock plate and vertical movement thereof. The lower edge of the lock plate 11 is suitably arched, as at 14. The side edges of the lock plate 11, 80 when in its vertically disposed position, engages the inner face of the stop flanges 7 of the coupler head 1 to prevent forward arcuate movement thereof from any cause whatsoever. 85

The means for locking the lock plate 11 against accidental vertical displacement consists of a bail member 15 the arms 16 of which are pivotally connected to the extended ends of the lock plate supporting pin 12. 100 The bail member is provided with a looped member 17, the lower portion 18 of which is adapted to engage either of the stops 19 or 20 when the lock plate 11 is in its normally closed position, as will be apparent from Fig. 2, which prevents accidental vertical displacement of the lock plate 11. 105

The means for actuating the bail member

and the lock plate for raising the latter consists of a suitable hand lever 21 which extends to both sides of a car and is journaled in suitable bearings 22 which are fixed to the end of a car body. 23 represents a rod which connects the looped portion of the bail member with the operating hand lever 21. The forward end of the connecting rod 23 is looped, as at 24, and the lower portion of the loop midway its ends, as at 25 is lower than at its ends for releasing the lower portion of the loop from locked engagement with either stop 19 or 20 prior to lifting the lock plate 11 during an uncoupling operation.

A suitable draw bar 26 is integrally connected with and directed rearwardly from the rear wall 4 of the head 1.

The second coupling member of the car 20 coupler may for convenience be called a male coupling head and comprises a head member designated 27 from which extends rearwardly a suitable draw bar 28. The sides of the head 27 extend laterally beyond 25 the sides of the draw bar, as at 29 and the forward outer corners of the coupler head 27 are rounded, as at 30. The head 27 and its integral draw bar 28 are provided with a longitudinal passage 31 which is open at 30 its forward end. Slidably mounted in the passage 31 is a coupling bar 32 having a longitudinal slotted opening 33 and the forward bifurcated end 34. A suitable stop pin 35 is suitably carried by the draw bar 28 and passes through the slotted opening 33 of the coupling bar 32. This pin 35 prevents extreme outward displacement of the coupling bar 32 during the pulling operation thereof.

40 A suitable connecting bar 36 is pivotally connected by means of a pin 37, at its rear end to the bifurcated end 34 of the slideable coupling bar 32. The forward end of the connecting bar 36 is provided with an upwardly directed pulling shoulder 38 and the lower corner thereof is rounded, as at 39 to facilitate coupling operations. 40 represents a suitable L-shaped trigger member which is pivotally connected by means of 45 the pin 41 to suitable bearings 42 which are suitably fixed to the top face of the coupler head 27 near its forward end, as clearly shown in Figs. 1, 2, 4 and 6. The vertically disposed arm 43 of the trigger 40 has 50 its front lower corner rounded, as at 44 and its lower face flat, as at 45 for engagement with the upper face of the rear end of the connecting bar 36 which is disposed in the bifurcated end of the coupling bar 32 for 55 locking the connecting bar 36 in its extended position for coupling connection with coupling head 1. The lower rear corner of the connecting bar 36 is concaved, as at 60 46 to engage the rounded corner 44 of the trigger whenever the connecting bar 36 is 65

moved into a vertical position, as shown in full lines in Fig. 6, for shortening the length of the car when riding upon a cage. Each track is preferably provided with a suitable post 47 which the connecting bar 36 will 70 strike when a car is leaving a cage thereby automatically raising the connecting bar 36 to its normal horizontally disposed position, as shown in dotted lines in Fig. 7. Arm 48 of the trigger 40 is preferably provided with a suitable hand operated lever member 49 which extends laterally to each side of the car where they can be easily and quickly raised for releasing the arm 43 of the trigger from engagement with the 80 connecting bar 36 to permit the connecting bar 36 to fall and assume a vertically disposed position, as clearly shown in Fig. 7. The draw bar of each coupler is suitably connected to its respective car, as is manifest, and not believed necessary to illustrate, outside of dotted lines.

The operation of the coupler is as follows:

Assuming that two mine or other suitable 90 cars are connected together, as clearly shown in Figs. 1, 2 and 4 and it is desired to disconnect the coupling connection therebetween, the operator raises the hand operated lever 21 from either side of the car 95 which first releases the lower portion of the loop portion of the bail member 13 from locking contact with either of the stops 19 or 20 and brings the bail member to a substantial vertical position and then in its further upward movement raises the lock plate 11 free of engagement or interference with the pull shoulder 38 of the coupling connecting bar 36 thereby permitting the 100 two connected cars to be uncoupled, as is 105 manifest.

When it is desired to couple two cars together, the operator merely sees that the connecting bar 36 is raised to its horizontally disposed position, as clearly shown in 110 Figs. 2 and 4 and as the cars are moved together, the head of the connecting bar 36 strikes the lower portion of the lock plate 11 moving it in a rearward arcuate path 115 until the pull shoulder 38 has moved into the coupler head 1 a sufficient distance to cause the lock plate 11 to automatically move back to its normal vertical position by means of gravity, thereby automatically 120 coupling the cars and locking the coupling heads together.

Due to the large end opening 6 in coupler head 1 and the pin like structure of the connecting bar 36, it is evident that the connected cars can move about a very sharp 125 curve as indicated by connecting bar in dotted lines in Fig. 3.

It will be further observed from Fig. 5, that when two cars are bumped together, that the coupler heads 1 and 27 come into 130

end for end contact with each other, causing the coupler bar 32 and the connecting bar 36 to utilize the entire length of space provided for within the two coupler heads and 5 draw bar 28. The forward end of the connecting bar 36 at all times rests upon the bottom wall 2 of the coupler head 1 thereby preventing any possible chance of accidental uncoupling of the coupling heads due to 10 the fact that the pull plate or lock plate is locked against accidental vertical displacement by means of the bail member and its engaging stops.

15 The many advantages of the herein described invention will readily suggest themselves to those skilled in the art to which it appertains.

20 I do not wish to be understood as having limited myself to the exact details of construction shown and described, but desire to have it understood that the invention I have shown in the drawings is merely illustrative, as it is manifest that various minor changes 25 may be made in the form, shape and particular arrangement of parts without departing from the spirit of my invention, hence I reserve the right to make any such changes, or modifications as may fairly fall 30 within the scope of the appended claims when fairly construed.

What I claim is:

1. In a mine car coupler structure, a draw 35 bar, a hollow coupler head integral with the forward end of said draw bar, pull shoulders formed at the front open end of the coupler head, a swingable and vertically movable coupling member positioned within and at the forward end of the coupler head

and engageable with said shoulders when in its normal position, a yoke member pivotally 40 connected to said coupling member, a pair of spaced lugs directed upwardly and inwardly from the top of the coupler head to prevent accidental vertical displacement of the coupling member by engaging the yoke 45 member and an arcuately movable looped member engaging said yoked member for lifting the coupling member from coupled engagement with the coupling member of a companion coupler.

2. A coupler comprising a draw bar, a hollow coupler head, bumping flanges extending laterally from said head, inwardly directed full flanges at the mouth of said head, a pair of spaced lugs formed upon the top of said coupler head, said coupler head having an opening in its top wall between said lugs and the side walls of said head being provided with registered vertically disposed slotted openings, a coupling member positioned within the coupler head and normally in contact with the inwardly directed pull flanges, a pin passing through said coupling member and receivable in the slotted openings in the side wall of the coupler head, a yoked member pivotally connected to the ends of said pin, a lever for elevating the coupling member through the medium of said yoked member and a cross member carried by the yoked member 55 adapted to engage either of the aforesaid lugs to prevent accidental vertical displacement of the coupling member.

In testimony whereof, I have hereunto signed my name to the specification.

JOSEPH WESOLIK.
